UNITED STATES PATENT OFFICE.

ARTHUR LOSEY, OF BAY SHORE, NEW YORK, ASSIGNOR TO UNITED STATES CAST IRON PIPE & FOUNDRY COMPANY, OF BURLINGTON, NEW JERSEY, A CORPORATION OF NEW JERSEY.

APPARATUS FOR CASTING PIPE AND OTHER ANNULAR ARTICLES CENTRIFUGALLY.

Application filed December 30, 1925. Serial No. 78,389.

My invention relates to centrifugal pipe molds of the general type of the De Lavaud molds, as shown, for instance, in Patent No. 1,329,295 of January 27, 1920. In this type of mold the metal is introduced into the rotating mold through a runner, the mold being retracted during the pouring so that the metal is delivered in, so to speak, a rope like coil to the walls of the rotating mold. In this mode of casting pipe there is danger that the metal first delivered by the runner will be too cold so that it will not properly merge with the succeeding deliveries and hence the pipe casting may be defective. The object of my invention is to provide the mold with a receptacle, separate from the pipe mold proper, into which the metal first delivered by the runner can be delivered until metal of proper temperature and fluidity flows from the runner after which the metal is allowed to flow into the mold proper in the ordinary manner and my invention consists of a mold provided with such a receptacle and in the features of construction of the receptacle.

My invention will be best understood as described in connection with the drawing in which it is illustrated and in which

Figure 1 is a sectional elevation of a centrifugal pipe mold provided with my improvements showing also in section the runner by which metal is delivered to the mold.

Figure 2 is a similar sectional elevation showing a modification of the construction illustrated in Fig. 1.

Figure 3 is a sectional elevation of a centrifugal pipe mold adapted for casting bell ended pipes and provided with my improvements.

Figure 4 is a sectional elevation of a modified construction of pipe mold adapted for the casting of the pipe in a refractory lining of the mold and also provided with my improvements, and

Figure 5 is an isometric drawing showing my invention as applied to a construction in which two molds are simultaneously charged with molten metal, the use of which twin molds is made more feasible by equipping them with my improvements.

A, Figs. 1 and 2, is a metallic mold of the ordinary type used in the centrifugal cast-

ing of De Lavaud pipes without bell ends, A¹ indicating an annular end extension of the mold at the outer end of which extension is formed an annular recess A² and several notches indicated at A³. B indicates the end of the runner through which the molten metal is introduced into the mold and which is shown in Figs. 1 and 3 as having its delivery spout in registry with the metal receptacle which constitutes the essential feature of my invention. In the construction of Fig. 3 the body of the metal pipe mold is indicated at a, its bell extension at aa, and the final extension for the support of the metal reservoir is indicated at A¹. In the construction of Fig. 4 AA indicates the metal flask supporting the refractory lining AA¹, AA² indicating the tubular extension from the flask corresponding in position and function with the extension A¹ in the other modifications.

In the construction of Fig. 1 the metal receptacle for cold or dead metal is made up of a metal member C fitting in the extension A¹ and having an inwardly projecting wall C¹ and a seat C² in which is seated a member D, made up of refractory material forming, as shown, the end of the mold proper and a division wall between the receptacle for dead metal and the mold. The construction shown in Fig. 2 is similar to that shown in Fig. 1 except that the seat C² for the refractory member D is here shown as formed in a separate mold part C, C. In the construction of Fig. 3 the general construction of the mold receptacle is similar to that of Fig. 1, modified slightly to better adapt it for the casting of bell ended pipe, the member D being provided with a rearward extension D¹ forming a core for the bell end. The construction shown in Fig. 4 is essentially similar to that shown in Fig. 1 with only such modification as adapts it for use with the refractory lining AA¹. In Fig.

5 G indicates the bed of the machine and H the casing in which two centrifugal molds are supported and which constitutes in the De Lavaud system a water jacket surrounding the molds. I, I, indicate ladels, by tipping which the metal is poured into the troughs J, J, connected with the runners, which feed the molds with molten metal.

In operation the runner B has its delivery spout in registry with the receptacle for dead metal formed at the end of the mold. When the pouring first begins, and the operative 5 does not begin to retract the metal until he sees that the metal running from the spout is of proper temperature and fluidity, there-upon the mold is retracted, leaving a body F of dead metal in the receptacle and charg-10 ing the mold proper with metal, indicated at F¹, which is of proper temperature and fluidity to make a good casting. The metal flowing into the receptacle at the end of the mold is chilled by contact with the metal 15 member CC¹ and when the casting is complete the split ring E is removed and the members CC¹ and D, making up the recep-tacle, removed and replaced for another cast-ing, and, to get rid of the waste metal, which 20 has remained in the receptacle. The notches A³ facilitate the removal of the split ring and also are useful in case any metal gets into the groove A² and enable it to be readily pried out.

25 Where twin molds are used, as indicated in Fig. 5, my invention is especially useful, enabling a skilled operative to see that both spouts are running metal of proper fluidity

and temperature before the direction of the twin molds is effected for the pouring of the 30 metal.

Having now described my invention, what I claim as new and desire to secure by Letters Patent is:

1. A centrifugal pipe mold having an an-35 nular receptacle for molten metal at its end separated from the mold proper by a removable annular ridge.

2. A centrifugal pipe mold having an an-40 nular receptacle for molten metal built up of removable sections secured to the end of the mold.

3. A pipe mold having the features of claim 2 in which the metal receptacle is built up of an annular ridge member of non heat 45 conducting material separating the receptacle from the mold proper and a body and end member of metal.

4. A pipe mold having the features of claim 2, having a sleeve like extension of the 50 mold in which the removable sections making up the metal receptacle are secured.

In testimony whereof, I have signed my name to this specification, this twenty-ninth day of December, 1925.

ARTHUR LOSEY.
